Specification of Letters Patent.

Patented Oct. 8, 1918.

Application filed January 2, 1918. Serial No. 209,936.

To all whom it may concern:

Be it known that we, GEORGE A. ENSIGN and RUSSELL E. KLINGER, both citizens of the United States, and residents of Defiance, 5 in the county of Defiance and State of Ohio, have invented a new and Improved Copying-Lathe, of which the following is a full, clear, and exact description.

The invention relates to copying lathes 10 such as shown and described in the Letters Patent of the United States, No. 723,044, granted to Charles Seymour on March 17, 1903.

The object of the present invention is to 15 provide a new and improved copying lathe more especially designed for turning aeroplane propellers and similar articles which require duplication of parts on opposite sides of a common center.

20 With this and other objects in view, the invention consists of certain novel features of construction, as hereinafter shown and described, and then specifically pointed out in the claims.

25 A practical embodiment of the invention is represented in the accompanying drawings forming a part of this specification, in which similar characters of reference indicate corresponding parts in all the views.

30 Figure 1 is a perspective view of the copying lathe with an aeroplane propeller in position to be turned;

Fig. 2 is an enlarged plan view of the same;

35 Fig. 3 is an enlarged elevation of the driving end of the copying lathe;

Fig. 4 is an enlarged cross section of the revoluble work holder, the section being on the line 4-4 of Fig. 5;

40 Fig. 5 is a sectional plan view of the same;

Fig. 6 is an enlarged side elevation of the cross-head carrying the revoluble cutter head and the revoluble pattern contact; and

45 Fig. 7 is an enlarged central section of a portion of the adjusting means for adjusting the pattern contact relative to the cutterhead for making the cuts of more or less depth.

50 The copying lathe is mounted on a suit-

ably constructed bed 10, on which is held to slide longitudinally a carriage 11 moved forward and backward by the usual feed screw 12. On the carriage 11 is mounted to slide transversely a crosshead 13 on which is journaled a cutter head 14 of usual construction and provided with a pulley 15 connected by a belt with other machinery for continually rotating the cutter head 14. The cutter head 14 is adapted to act at the time 60 on the portion of the work to be formed into a blade 20 of an aeroplane propeller 21 usually provided with a hub 22 from which extends the aforesaid blade 20, and another blade 23, diametrically opposite the blade 65 20 and which blade 23 is likewise turned by the machine from the rough state on reversing the work in the machine, as herein-after more fully explained.

On the rear of the crosshead 14 is mounted to slide transversely a slide 30 in which is journaled a pattern contact 31, preferably in the form of a wheel, in contact with a pattern 32, which, as shown, is in the form of a blade of a propeller wheel. The pattern 32 is held at one end on a headstock spindle 33 and at the other end on a tailstock center 34, and the headstock spindle 33 is journaled in a suitable bearing 35 formed on a headstock 36 attached to or 70 forming part of one end of the bed 10. The tailstock center 34 is mounted to turn in a tailstock rod 37 held longitudinally adjustable in the usual manner in a bearing 38 mounted on a tailstock 39 adjustably secured 75 on the bed 10. Springs 40 connect the carriage 11 with the crosshead 13 to hold the pattern contact 31 at all times in contact with the revolving pattern 32.

The outer end of the blade 20 is held on 80 a revoluble tailstock center 50 mounted to turn in a tailstock rod 51 mounted to slide in the usual manner in a bearing 52 arranged on the front of the tailstock 39. The head and tailstocks 36 and 39 are connected 85 with each other by a suitable tie-rod 55 to give the desired stability to the tailstock 39.

Through the bore 24 of the hub 22 of the propeller 21 extends a pin 60 terminating at 100 one end in a head 61 abutting against the

front face of the hub 22 and held in a longitudinally extending arm 62 of a bracket 63 adjustably secured by a bolt 64 to the right-hand end 65 of a tubular work holder 66, 5 the said bolt 64 extending through a slot 67 formed in the bracket 63 to allow of readily adjusting the said bracket on the end 65 of the work holder 66. A set screw 68 screws in the end 65 of the work holder 66 and 10 abuts against the outer end of the bracket 63 to permit of accurately adjusting the bracket 63 at the time the bolt 64 is loosened. After the desired adjustment is made the bolt 64 is screwed up. The head 61 previously 15 mentioned is provided with a flange 69 seated on the front of the bracket member 62, as plainly indicated in Figs. 4 and 5, and the head 61 is provided with a polygonal recess 70 for the application of a suitable 20 tool for turning the head 61, as hereinafter more fully described. The rear end of the pin 60 is provided with a screw thread 71 which screws in a nut 72 fastened by a key in a longitudinally extending member 74 25 formed on a bracket 75 adjustably secured on the end 65 by a bolt 76 extending through an elongated slot 77 formed in the bracket 75. A set screw 78 similar to the set screw 68 serves to adjust the bracket 75 in a radial 30 direction after the bolt 76 is loosened, and when the desired adjustment is made the bolt 76 is screwed up to fasten the bracket 75 in place. The nut 72 is provided with a flange 79 abutting against the rear face of 35 the member 74 while the forward end of the nut 72 abuts against the rear face of the hub 22 so that the latter is clamped between the head 61 and the nut 72 to securely hold the hub centrally in position relative to the work 40 holder 66. As previously stated, the work holder 66 is made tubular to permit the blade 23 to extend through the tubular work holder during the time the other blade 20 is turned by the cutter head 14 according to 45 the shape of the pattern 32. After the blade 20 is finished the pin 60 is unscrewed from the nut 72 and removed from the bore 24 of the hub 22 and then the propeller is reversed and the blade 23 is engaged with the tail- 50 stock center 50 and the pin 60 is replaced so that the blade 20 extends through the tubular work holder 66 while the blade 23 is in position to be acted on by the crosshead 14 to turn the blade to the correct shape, that 55 is, to that of the pattern 32.

The work holder 66 is journaled in a half bearing 80 formed on the front end of the headstock 36 and to this half bearing 80 are attached bearing straps 81 completing the 60 bearing for the said work holder 66. The half bearing 80 and the straps 81 abut against annular flanges 82 and 83 formed exteriorly on the work holder 66 to hold the latter against longitudinal displacement. 65 On the flange 83 is secured or formed a gear

wheel 90, and a similar gear wheel 91 is secured on the headstock spindle 33 and the two gear wheels 90 and 91 are connected by a gearing 92 with a main shaft 93 provided with a pulley 94 connected by belt with other machinery for imparting a rotary motion simultaneously to the gear wheels 90 and 91 to rotate the same in unison and consequently to rotate the propeller 21 and the pattern 32 in unison with each other. 70

In order to impart the desired forward and backward motion to the carriage 11 by the feed screw 12, it is necessary to rotate the latter alternately in opposite directions and for this purpose the feed screw 12 is connected by a suitable changeable gearing 100 with a main driving shaft 101 carrying loose pulleys 102, 103 (see Figs. 1, 2 and 3) connected by belts with suitable machinery for rotating the pulleys in opposite directions. 80 The pulleys are adapted to be engaged by the usual clutch mechanism 104 controlled by a shifting rod 105 provided with the usual stops 106 and 107 adapted to be engaged by the sides of the carriage 11 so that the latter 90 alternately actuates the stops 106 and 107 to shift the rod 105 whereby the clutch mechanism 104 alternately connects the pulleys 102 and 103 with the main driving shaft 101. Thus the main driving shaft 101 is alternately rotated in opposite directions and a similar movement is given to the feed screw 12 to move the carriage 11 forward and backward on the bed 10. The carriage 11 is provided with a sectional nut device 110 of 100 usual construction for connecting the carriage 11 with the feed screw 12 or for disconnecting the carriage from the said feed screw whenever it is desired to stop the automatic feed of the carriage to allow of 105 running the carriage forward or backward by hand. This hand feeding device of the carriage 11 is of usual construction so that further description of the same is not deemed necessary. 110

When the machine is running the work and the pattern 32 are rotated in unison and the pattern contact 31 is in contact with the pattern 32 thus positioning the cutter head 14 correspondingly relative to the rough part 115 of the work to fashion the latter into a blade 20 according to the pattern 32. When the blade 20 has been finished the machine is stopped and the work is now reversed in the work holder 66, as previously explained, so 120 that the other portion of the rough work is subsequently fashioned into a blade 23 on repeating the above described operation.

In order to regulate the depth of the cut made by the cutter head 14 on the work, it 125 is necessary to adjust the pattern contact 31 nearer to or farther from the cutter head 14, and for this purpose the following arrangement is made, special reference being had to Figs. 6 and 7: On the bracket 30 130

carrying the pattern contact 31 is secured or formed a nut 120 in which screws the rear threaded end 121 of a transversely extending rod 122 journaled in the front end 5 of the crosshead 13. The front end of the rod 122 is provided with a threaded portion 123 on which screws a nut 124 abutting against the hub of a wheel 125 connected by a key 126 with the rod 122, the key engaging a 10 keyway in the said rod to allow the wheel 125 to slide lengthwise on the rod 122 and to turn the same on turning the wheel 125. A sleeve 127 is loosely held on the rod 122 between the front end of the crosshead 13 and the rear end of the wheel 125. A stop collar 128 is secured on the rod 122 and abuts against the rear face of the front of the crosshead 13. On the operator turning the wheel 125 in one direction, the rod 122 15 is similarly turned, and its threaded end 121 screwing in the nut 120 moves the crosshead 13 rearwardly and with it the cutter head 14, and when the wheel 125 is turned in the opposite direction then the crosshead 13 is 20 moved forwardly and with it the cutter head 14. After the desired adjustment is made, the nut 124 is screwed up to securely clamp the wheel 125 in position against the sleeve 127 thus locking the rod 122 against 25 accidental turning.

In order to indicate the adjustment made, a gage rod 130 is attached to the slide 30 and its forward end longitudinally engages a bearing 131 attached to the forward portion 35 of the crosshead 13. This end of the gage rod 130 is provided with a scale 132 which indicates on the bearing 131 so that the operator can readily determine the amount of adjustment given to the crosshead 13 and the cutter head 14 to regulate the depth of the cut of the cutter head 14 relative to the work. It is understood that by moving the crosshead 13 and with it the cutter head 14 forwardly as described, a 40 deeper cut is made, and on adjusting the crosshead 13 and the cutter head 14 in a rearward direction a cut of lesser depth is made.

After the work has been turned to the 50 desired shape according to the pattern 32 the crosshead 13 is moved rearwardly to disengage the cutter head 14 from the work and thus to allow convenient removal of the same and reversing thereof, as previously 55 explained, to fashion both blades 20 and 23 according to the pattern 32. In order to impart this rearward movement to the crosshead 13 use is made of a link 140 pivotally connecting the crosshead 13 with a bell 60 crank lever 141 fulcrumed on the carriage 11 and under the control of the operator standing in front of the machine. When the lever 141 is swung from the left to the right the link 140 pushes the crosshead 13 65 rearwardly against the tension of its spring

40. The lever 141 when in its extreme right-hand position with the short arm of the lever 141 abutting against a stop pin 142 attached to carriage 11 is past a central position thus holding the crosshead 13 locked 70 in rearmost position until the lever 141 is again returned to its left hand position after the work has again been placed in position on the work holder 66 and the tailstock center 50, as previously explained. 75

From the foregoing it will be seen that by the arrangement described, the blades of aeroplane propellers and similar articles can be readily and accurately fashioned 80 from a single piece of wood and in proper relation to the center of the propeller as the bore of the hub of the propeller is engaged by the attaching pin 60 thus locating both ends of the stick of wood in correct relation to the pattern. 85

It will also be noticed that by making the work holder 66 tubular and out of the path of its driving gear or the carriage driving gear, the end of the stick inactive at the time can readily project through the 90 work holder without the slightest interference by any of the parts of the machine.

It will further be noticed that by the arrangement described, the work can be readily placed in position on the work holder 95 and the tailstock center 50 and reversed to insure formation of a large number of propellers in a comparatively short time.

Having thus described our invention, we claim as new and desire to secure by Letters 100 Patent:—

1. In a copying lathe, a revoluble tubular work holder provided at one end with oppositely disposed brackets adapted to receive the hub of the work between them, and a 105 pin provided with an integral head at one end and a nut screwing on the other end, the head being mounted to turn in one bracket and the nut being held against turning in the other bracket, the head and nut 110 being adapted to engage the faces of the hub of the work to clamp the latter in place in the tubular work holder at a point beyond one end thereof.

2. In a copying lathe, a tubular work 115 holder provided at one end with oppositely disposed adjustable brackets provided with parallel members projecting beyond one end of the holder, a pin adapted to extend through the hub of the work and provided at one end with a head engaging one of the said bracket members, the head having a flange seated on the said bracket member, a nut in which screws the outer end of the said pin, the nut being held in the other 120 bracket member and having a flange seated on this bracket member, the said head and the said nut clampingly engaging the hub of the work at the opposite sides thereof. 125

3. In a copying lathe, a tubular revolu- 130

ble work holder, diametrically opposite brackets held radially adjustable on one end of the said work holder and provided with parallel longitudinally extending members, 5 a pin adapted to extend centrally through a bore in the middle of the work, the pin having at one end a head mounted to turn

in one of the said members, and a nut held in the other member and in which screws the threaded end of the said pin, the said head and the said nut being adapted to clamp the work between them.

GEORGE A. ENSIGN.
RUSSELL E. KLINGER.

Copies of this patent may be obtained for five cents each, by addressing the "Commissioner of Patents, Washington, D. C."
